UNITED STATES PATENT OFFICE.

WALTER T. GORTON, OF THE UNITED STATES ARMY.

RECEIVER FOR MACHINE GUNS.

Application filed July 12, 1922. Serial No. 574,556.

(FILED UNDER THE ACT OF MARCH 3, 1883, 22 STAT. L., 625.)

To all whom it may concern:

Be it known that I, WALTER T. GORTON, captain, Ordnance Department, United States Army, a citizen of the United States,

5 stationed at Springfield Armory, Springfield, Massachusetts, have invented an Improvement in Receivers for Machine Guns, of which the following is a specification.

10 The invention described herein may be used by the Government, or any of its officers or employees in prosecution of work for the Government, or by any other person in the United States, without payment to me of any royalty thereon, in accordance 15 with the act of March 3, 1883.

The subject of this invention is a receiver for machine guns.

In the present design of the Browning machine guns, the bottom plate of the receiver is a flat member assembled between the side plates by means of a dove-tail construction, grooves for which are located near the lower edge of the interior of the side plates. The edges of the bottom plate 25 are formed into tongues which are clamped in these grooves in the side plates by a rolling operation performed on the under edges of the side plates.

This construction has been found to be 30 weak, particularly so at the forward end of the bottom plate, where failure has frequently occurred due to the strain set-up by the breech mechanism of the gun. Several forms of riveted sections for assembling the 35 side and bottom plates have been proposed but these all include a bottom plate of inverted channel section with the side plates correspondingly widened to provide for riveting. These designs have the disadvantages of requiring considerably more material, increasing weight and increasing 40 the size of the receiver of the gun. In addition to this it is necessary to provide tongues and grooves for properly positioning the plates with respect to each other, and for manufacturing reasons these 45 grooves must necessarily be made in the side plates. This means that the plates are weakened corresponding to the depth 50 of the grooves, and hence the strength of the section is limited by that of the plates rather than that of the riveted joint.

The object sought in the improvement under consideration is the provision of a riv-

eted assembly of maximum strength and 55 particularly to avoid weakening the side plates by grooves which prevent the full strength of the rivet joint being utilized.

This object is accomplished specifically by means of a bottom plate of upright U- 60 section which is assembled so as to embrace the lower edges of the two side plates. A groove is cut in the exterior surface of each side plate near its lower edge, and these 65 grooves are engaged by corresponding tongues formed on the interior of the upright portions of the bottom plate. The rivets which hold the joints securely together are located above these tongues and grooves. This construction provides for a 70 very rigid support of the side plates and permits of conveniently forming two lugs on the lower side of the bottom plate to act as the elevating bracket for the rear mounting pin. 75

With these and other objects in view my invention resides in the novel arrangement and combination of parts and in the details of construction hereinafter described and claimed, it being understood that changes in 80 the precise embodiment of the invention herein disclosed may be made within the scope of what is claimed without departing from the spirit of the invention.

A practical embodiment of the invention 85 is illustrated in the accompanying drawing, wherein:

Fig. 1 is a view in side elevation of a receiver constructed in accordance with the invention, the cover and top plate of the receiver being removed; 90

Fig. 2 is a bottom plan view of the same and

Fig. 3 is an end elevation, partly in section. 95

Referring to the drawing by numerals of reference:

Side plates 10 have longitudinal grooves 11 formed in their outer faces near the lower edges thereof. The bottom plate 12 100 is of channel formation and embraces the side plates and has upon the inner surface of its up-standing ribs tongues 13 which engage in the grooves 11. The up-standing ribs are apertured above the tongues 13 for 105 the reception of rivets 14 by which the side plates are securely fastened to the bottom plate and, because of the location of such

rivets, the strength of the joint between the bottom plate and side plate will be that of the riveted connection and will not be affected by the groove 11 cut in side plate.

5 I claim:

1. A receiver for machine guns, including side plates, each formed with a longitudinal groove in its outer face near its lower edge, a bottom plate of channel formation embracing the side plates, each up-standing member of the bottom plate having a longitudinal rib on its inner surface adapted to enter the groove in the side plate and a riveted joint between each up-stand-
- 10

ing member of the bottom plate and a side 15 plate, said joint located above the tongue and groove connection.

2. A receiver for machine guns, including side plates each formed with a longitudinal groove near its lower edge, a bottom plate of channel formation, each flange of the bottom plate having a longitudinal rib adapted to enter the groove in a side plate and a riveted joint between each flange of the bottom plate and a side plate, 20 25 said joint located above the tongue and groove connection.

WALTER T. GORTON.
